UNITED STATES PATENT OFFICE.

HENRY R. ENGLERT, OF NEW YORK, N. Y.

DESIGN FOR A METALLIC PLATE.

SPECIFICATION forming part of Design No. 31,208, dated July 11, 1899.

Application filed April 11, 1899. Serial No. 712,667. Term of patent 14 years.

To all whom it may concern:

Be it known that I, HENRY R. ENGLERT, a citizen of the United States, residing in the city, county, and State of New York, have invented and produced a new and original Design for a Metallic Plate, of which the following is a specification, reference being had to the accompanying drawing, forming a part thereof.

10 The accompanying drawing shows my new design for a metallic plate.

As shown, the leading or material feature of my design consists in the plate having

thereon the representation of a palette, upon which is Hogarth's line of beauty, with the 15 representation of a graver extending through the thumb-hole of the palette.

What I claim as new, and desire to secure by Letters Patent, is—

The design for a metallic plate herein shown 20 and described.

HENRY R. ENGLERT.
